(57) **CLAIM**

The ornamental design for a conveyor belt cleaner blade, as shown and described.

DESCRIPTION

FIG. 1 is a front, right, top perspective view of a first embodiment of a conveyor belt cleaner blade, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right end elevational view thereof, the left end elevational view being mirror image;

FIG. 7 is a front, right, top perspective view of a second embodiment of the conveyor belt cleaner blade;

FIG. 8 is a front elevational view thereof;

FIG. 9 is a rear elevational view thereof;

FIG. 10 is a top plan view thereof;

FIG. 11 is a bottom plan view thereof;

FIG. 12 is a right end elevational view thereof, the left end elevational view being mirror image;

FIG. 13 is a front, right, top perspective view of a third embodiment of the conveyor belt cleaner blade;

FIG. 14 is a front elevational view thereof;

FIG. 15 is a rear elevational view thereof;

FIG. 16 is a top plan view thereof;

FIG. 17 is a bottom plan view thereof; and,

FIG. 18 is a right end elevational view thereof, the left end elevational view being a mirror image.

The dashed broken lines show portions of the conveyor belt cleaner blade that form no part of the claimed design. The conveyor belt cleaner blade shown including broken lines in FIGS. 13-18 is shown with a symbolic break in its length. The appearance of any portion of the conveyor belt cleaner blade between the break lines forms no part of the claimed design.
